UNITED STATES PATENT OFFICE.

DANIEL FREDERICK McGOVERN, OF MONTPELIER, VERMONT.

POLISHING MACHINE.

1,411,923.

Specification of Letters Patent.

Patented Apr. 4, 1922.

Application filed April 10, 1920. Serial No. 372,896.

To all whom it may concern:

Be it known that I, DANIEL F. McGOVERN, a citizen of the United States, residing at Montpelier, county of Washington, State of Vermont, have invented certain new and useful Improvements in Polishing Machines, of which the following is a specification.

This invention relates to polishing machines and particularly to a machine of the swinging arm type. In machines of this sort it is of great practical advantage to have the arm capable of a complete swing about its support. A capacity for such movement greatly enlarges the output of the machine as it is available for work on all sides of its mounting. In heavier machines it is important that the mounting be fixed and of a permanent nature, and work for a machine so installed must therefore be presented to the machine or within its working range.

In my present invention I have provided a machine of great stability and endurance and one having a wide working area as well as an easy operation and adjustment through that area. The form of my machine herein shown is a practical embodiment found entirely satisfactory in yard or shed. Throughout the specification and the drawings showing this illustrative embodiment like reference characters are employed to indicate corresponding parts, and in the drawings:

Fig. I is a side elevation of the machine.

Fig. II a detail of the head.

Fig. III a section through the center arm shaft.

Fig. IV a detail of the arm bearing on the column, and

Fig. V a vertical sectional view through the spindle.

My machine comprises a base 1 bearing a vertical column 2 having a head 3 rotatably mounted on the top of the column. The arm comprises a cylindrical bearing 4 which surrounds the column 2 from which is extended a pair of frame or ladder arms 5—5 braced by a web 5¹. The ends of the arms 5—5 have bearings 6 in which swing the bearing ends of an arm extension 7. At the other end of the arm extension 7 are bearings 8 in which is the vertical work spindle 9.

Within the vertical column 2 which is fixed on the base 1 is a shaft 10 driven by suitable

gearing from a power shaft 11. On the upper end of the shaft 10 is a pinion 12 which through an idler 13 and a meshing pinion 14 drives the shaft 15. The shaft 15 has a bearing 16 in the head 3 and also has bearings at 17 and 18 in the column 2 bearing 4. Between the bearings 17 and 18 is mounted a pulley 19 splined to the shaft 15 so that the arm 5 together with the pulley may be vertically raised and lowered on the column 2. The shaft 15 of the pulley 19 is disposed opposite to the arm 5 and extension 7. On the opposite side of the shaft 15 is a fixed guide rod 20 carried by the head 3 and extending down through the arms 5 so as to balance, guide and steady the arm and head 3 in all positions of vertical adjustment and swing.

It is to be noted that the interposition of the idler 13 has the effect of offsetting any creeping tendency of the arms 5 about the column 2. While the location of the pulley on the opposite side of the column 2 from the arm might be shifted to the other side, it is advantageous in the balance of the machine. The idler however balances any creeping tendency and leaves the arm uninfluenced by planetary movement which otherwise would be present.

On the same side of the bearing 4 is a multiple pulley 21 and on the head 3 directly above it is a corresponding pulley 22. The chain or cable indicated at 23 is passed about these pulleys and preferably made fast at one end to the head 3. The other end is brought around a pulley 24 and carried to a drum 25 mounted on the arm 5. The shaft 25¹ is suitably connected to a shaft 26 fitted with a hand wheel 26¹ and having at its other end a bevel friction wheel 26² which may be brought in contact with either the friction wheel 27 or 28 of the shaft 30. These friction wheels are shiftable by a bell crank 31 connected by link 32 with a bent lever 33. The end of the lever 33¹ is brought down to a convenient position in relation to certain other levers hereinafter to be described so as to make the control of the machine within the immediate hand grasp of the operator.

The shaft 30 as more clearly appears in Fig. III is suitably bushed and journaled within the sleeves 30¹ within the bearings 6 of the arms 5. The arms 7 have bearings

7¹ through which the sleeves 61 are passed and fixed by suitable set screws. Between the arms 7 are a pair of pulleys 34 and 35. The pulley 34 is belted to the pulley 19, the 5 pulleys being of such diameter that the belt passes freely around the web 5¹ and the column 2. The pulley 35 is connected by a second belt to the pulley 36 on the work spindle 9. The pulley 36 is loose on the 10 spindle 9 but carries a clutch 37 adapted to be engaged by a corresponding clutch member 38 splined indirectly to the spindle 9. The clutch member 38 is keyed on a hollow sleeve 60 held between the main bearings 61 of the shaft 9. Through this sleeve 60 the spindle 9 passes, and to it the spindle 9 is keyed. This splining to the spindle 9 permits the vertical movement of the spindle as far as the limiting stops 39 permit. The 15 movement of bringing the tool carried by the work spindle into engagement with the work is effected by a hand lever 40 having a hand grasp 40¹ and pivoted at its opposite end 40² to a bracket 41 on the lower side 20 of the arm. The clutch member 38 is moved by a lever 42 pivoted at 43 in a bracket 44 and connected by a link indicated in dotted lines at 45 to the inner end of a lever 46 pivoted as indicated in broken lines at 47. 25 The inner end of this lever 46 indicated at 46¹ lies just above the hand grasp 40¹ of the spindle lever 40.

The pivoting of the arms, the disposition of the pulleys and the belting permits the 30 work spindle to be carried around through a complete circle or surrounding zone lying entirely about the column 2. The head 3 is so balanced and mounted on the column 2 that the arm 5, 7 is moved with very little 35 effort. The head 3 runs on ball bearings 3¹ interposed between its lower face and an annular bracket 2¹ carried on the column 2. The head 3 has the bearing 10¹ of the shaft 10 disposed centrally of it and the bearing 40 45 16 of the shaft 15 and the rod 20 are symmetrically disposed on opposite sides so that they also balance, guide and steady the head.

The bearings 4 of the arms 5 enclosing 50 the column 2 are provided with an annular pocket or recess as at 50 and in this annular pocket are located an annular anti-friction set. This set consists of a hardened sleeve 51 enclosing the column 2 and a corresponding larger annular sleeve 52 set 55 against the back wall of the pocket 50. Between these sleeves 51 and 52 is a roller bearing consisting of a plurality of rollers 53 carried in a suitable cage 54. The arm 5 60 has therefore a great freedom and ease of rotation about the column 2. Furthermore on account of the position of the pulley 19 the driving strain is very evenly balanced and taken up against the column 2 which 65 lies between it and its driven pulley 34.

The roller bearing in the pocket 52 is closed by a cap 55 and sealed by a packing 56 which prevents the entry of any dust or grit within this bearing as the arm is vertically adjusted.

Although the arms 5, 7 may be raised by 70 the hand wheel 26, vertical adjustment of the arm as well as its control, otherwise is effected through the lever group 33, 46 and 40. As will be seen in Fig. I, the ends of these levers 33¹, 46¹ and 40¹ are disposed in 75 a convenient juxtaposition so as to be within the immediate grasp and control of the operator at the work spindle end of the arm. This permits a positive and immediate control of the arm in any position of the arm 80 through the entire 360° of swing and in any radial position in the zone about the column 2.

Various modifications in the construction and operation of my device may obviously 85 be resorted to if within the limits of the appended claims.

What I therefore claim and desire to secure by Letters Patent is:

1. In a polishing machine, a fixed hollow column, a revoluble head thereon, a central vertical drive shaft therein and extending through said head, an arm having a bearing embracing said column, a pulley on said bearing on the opposite side of said arm, a shaft for said pulley and splined thereto, said shaft being journaled in said head and geared to said drive shaft. 90

2. In a polishing machine, a fixed hollow column, a revoluble head thereon, a central vertical drive shaft therein and extending through said head, an arm having a bearing embracing said column, a pulley on said bearing on the opposite side of said arm, a shaft for said pulley and splined thereto, said shaft being journaled in said head and geared to said drive shaft, an extension arm pivoted to the end of said first-named arm, a shaft in the axis of said arm pivot, a pair of pulleys on said shaft, a 100 work shaft at the end of the extension arm, and a drive for said work shaft. 105

3. In a polishing machine, a fixed hollow column, a revoluble head thereon, a central vertical drive shaft therein and extending through said head, an arm having a bearing embracing said column, a pulley on said bearing on the opposite side of said arm, a shaft for said pulley and splined thereto, said shaft being journaled in said head and 110 geared to said drive shaft, an extension arm pivoted to the end of said first named arm, a work shaft at the end of the extension arm, and a drive pulley for said work shaft. 115

4. In a polishing machine, a fixed hollow column, a revoluble head thereon, a central vertical drive shaft therein and extending through said column and head, an arm having a bearing embracing said column, a pulley arm, a shaft geared to said drive shaft 120 125 130

and mounted on said head and passing through said arm, and a pulley on said bearing and splined thereto.

5. In a polishing machine, a fixed hollow column, a revoluble head thereon, a drive shaft extending through said column and head, an arm having a bearing embracing said column, a pulley on said arm, a shaft for said pulley and splined thereto, said shaft being journaled in said head and geared to said drive shaft, an extension arm pivoted to the end of said first named arm, a shaft in the axis of said arm pivot, and a pair of pulleys on said last named shaft.

10 6. In a polishing machine, a fixed hollow column, a revoluble head thereon, a drive shaft extending through said column and head an arm having a bearing embracing said column, a pulley on said arm, a shaft 20 for said pulley and splined thereto, said shaft being journaled in said head and geared to said drive shaft, an extension arm pivoted to the end of said first named arm, a shaft in the axis of said arm pivot, a pair 25 of pulleys on said shaft, a work shaft at the end of the extension arm and a drive pulley for said work shaft.

7. In a polishing machine, a fixed column and a head rotatably mounted on the top 30 thereof, an arm rotatably and slidably mounted on said column, and a pair of shafts disposed one on each side of said head and slidably engaging said arm.

8. In a polishing machine, a fixed column, 35 and a head rotatably mounted on the top thereof, an arm rotatably and slidably mounted on said column, and a pair of shafts disposed one on each side of said head and geared to each other and slidably engaging 40 said arm.

9. In a polishing machine, a fixed column, a revoluble head thereon, a central drive shaft passing through said head and having 45 a pinion thereon, a second vertical shaft carried by said head outside of said column,

and having a pinion at its upper end, and an intermediate pinion on said head and engaging said two first named pinions.

10. In a polishing machine, a fixed hollow column, a revoluble head thereon, a central 50 vertical drive shaft therein and extending through said column, an arm having a bearing embracing said column, a pulley on said arm, a shaft mounted on said head passing through said arm, a pulley on said bearing and splined thereto, a pinion on the vertical drive shaft, a pinion on said pulley shaft, and a pinion on said head intermediate of said pinions.

11. In a polishing machine, a fixed hollow 60 column, a revoluble head thereon, a central vertical drive shaft therein and extending through said column, an arm having a bearing embracing said column, a pulley on said arm, a shaft mounted on said head passing 65 through said arm, a pulley on said bearing and splined thereto, a pinion on the vertical drive shaft, a pinion on said pulley shaft, and a pinion on said head intermediate of said pinions, an extension arm pivoted at 70 the end of the first-named arm, a shaft in the axis of said arm pivot, a pair of pulleys on said shaft, a work shaft at the end of said extension arm, and a drive pulley on said 75 shaft.

12. In a polishing machine, a fixed column, a central vertical drive shaft therein and extended through said column, an arm having a bearing embracing said column, a pulley on said bearing, a shaft passing through said 80 bearing, a pulley on said bearing and splined to said shaft, a pinion on the vertical drive shaft, a pinion on said pulley shaft, and an idle pinion intermediate of said pinions.

In testimony whereof I affix my signature 85 in presence of two witnesses.

DANIEL FREDERICK McGOVERN.
